Primary Examiner — Mitchell I. Siegel(74) *Attorney, Agent, or Firm* — Bass Patent Law, LLC(57) **CLAIM**

The ornamental design for a handle gripping structure, as shown and described.

DESCRIPTION

FIG. 1 is a front, right side perspective view of a design for a handle gripping structure;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing is included for the purpose of illustrating unclaimed subject matter and forms no part of the claimed design.

1 Claim, 6 Drawing Sheets(56)
